CONTAINER STRUCTURE

Fred Y. McKenney, Red Bank, Tenn., assignor to
 Cumberland Case Company, Chattanooga,
 Tenn., a corporation of Tennessee

Application November 24, 1937, Serial No. 176,324

2 Claims. (Cl. 217—69)

The present invention relates to a container structure, and, more particularly, to a structure for bracing and reinforcing boxes and other containers.

5 The invention is herein shown and described applied to a milk bottle crate, but it will be understood that the invention is applicable to containers of various types.

An important object of the invention is to provide a reinforcing structure for the corners and edges of containers.

In various types of boxes and other containers, including crates such as are used for holding milk bottles, the bottom and corner portions of the 15 container are subjected to heavy wear due to the fact that the containers are frequently dropped or moved against each other with some force. Crates of the milk bottle type, for example, ordinarily have their side walls formed of wood and 20 it is therefore desirable that the edges and corners of the wood frame be securely braced. By the present invention, bracing elements are applied to the corners and to at least the lower edges, and these bracing members are secured to 25 or include a wear member so that the entire bracing structure is securely held together.

Another important object of the invention is to provide a wear member at the corner of a container which will serve to receive most of the 30 wear to which the container is subjected.

Other objects and advantages of the invention will be apparent from the following specification and from the drawing, wherein:

Figure 1 is a plan view of a milk bottle crate, 35 including the structure of the present invention, a portion of the view being in horizontal section.

Figure 2 is a transverse vertical sectional view on the line 2—2 of Figure 1, the view being on a slightly larger scale than Figure 1.

40 Figure 3 is a vertical sectional view on the line 3—3 of Figure 1, that is, through a corner of the crate.

Figure 4 is a horizontal sectional view on the line 4—4 of Figure 2, and

45 Figure 5 shows, in disassembled relation, elements included in the structure of the present invention.

The milk crate illustrated in the drawing includes the usual end walls 10 and 11 and side walls 12 and 13, the bottle spacing wires being 50 designated by the numeral 14.

The lower edges of the walls of the crate are provided with metal runners 15 of U-shaped form, the lower edges of the walls preferably being undercut as shown in Figure 2 so that the 55

outer side surfaces of the runners will lie flush with the side surfaces of the walls. The corners of the crate are joined together and braced by inner and outer bracing members 16 and 17, respectively, these elements being angled so that, together, they embrace the adjoining ends of the walls as best shown in section in Figure 1. The inner bracing members 16 may be grooved as indicated at 18 to support the spacing wires 14 and the upper ends of these braces 16 may extend 10 above the upper edges of the walls to provide stacking irons 19.

As best shown in Figure 5, the lower walls of the runners 15 are upwardly and centrally recessed. By this arrangement, the side flanges of 15 the runners 15 are prevented from spreading apart or opening out when the crate is dropped or otherwise receives blows upon its lower surface.

In the embodiment shown in the drawing, the 20 outer corner bracing members 17 are shown as having rounded corners. However, it will be obvious that these corners could be squared. In any event, if rounded corners are used, the ends 25 of the slats of the crate walls would be beveled to fit the corner curvature of the outer corner braces.

In order that the metal bracing elements of the 30 crate, that is, the runners 15 and corner braces 16 and 17, may be securely held together and full 35 protection against wear provided at the lower corners of the crate, I provide a wear element 21 at such lower corners. The wear element 21 is preferably in the form of an angled metal casting or solid metal body as best shown in Figures 4 40 and 5 and includes two arms 26 and 27. Flanges 28 are provided at the lower edges of the inner and outer surfaces of the walls of the arms 26 and 27 so that extensions 29 of the side walls of the adjacent runners may overlie these flanges. Each wear element 21 is adapted to be positioned 45 in a cut-out 30 provided at each lower corner of the crate so that these walls will be more firmly braced at this point. Also, each cut-out 30 is notched at its upper surface to receive bosses 31 formed on the upper surfaces of the arms of the wear member so that the wear member will be firmly interlocked in the walls of the crate.

In assembling the bracing elements of the 50 crate, the extensions 29 of the runners 15 are positioned to fit against the side surfaces of the wear member 21 and to have their lower edges rest upon the flanges 28. The lower ends of the corner bracing elements 16 and 17 are then applied with their lower ends against the extensions 55

29 as shown in Figure 4. The bosses 31 of the wear member are provided with apertures 32 with which apertures 33 in the corner bracing elements 16 and 17 are aligned. Rivets, bolts, or other securing means 33a may then be passed through the aligned apertures, such securing means also extending through slots 34 provided in the extensions 29 of the runners so that the entire bracing structure will be secured together 10 and the various elements thereof secured against relative movement.

It is desirable that the runners 15 be provided with apertures of slot form so that any inequality in the length of the wooden slats of the walls 15 may be accommodated. However, it will be apparent that when the entire bracing structure is secured together, the runners 15 will not have any movement with respect to the wear members 21 because the securing elements 33a will clamp 20 the bracing elements securely together.

As best indicated in Figure 4, the flanges 28 of each wear member are sufficiently wide to extend beneath both the extensions 29 of the runners and the lower ends of the corner braces 16 and 25 17. In order that the outer surfaces of the outer corner braces 17 may lie flush with the walls of the crate and also with the outer walls of the runners, the extension 29 at the outer side of each runner is offset inwardly as shown in Figure 4.

30 It will be observed that the above arrangement provides at the lower corners of the container or crate a solid member capable of taking a maximum of wear such as would result from the sliding of the crate over any surface, and which will 35 also withstand impacts received from dropping. Furthermore, all of the bracing elements of the crate are securely locked together by a solid body, that is, a body of hard material and of substantial dimensions locked in the frame of the 40 crate and which solid body underlies the edges of the other bracing elements at the corner of the crate.

In the usual crate all of the bracing elements which meet at the lower corners of the crate are 45 subject to wear. Whenever these elements be-

come so worn as to be useless, the entire crate must be discarded, because the expense of replacement would approximate the cost of a new crate. By the present arrangement, the wear members 21 completely protect the other bracing 5 elements from wear. If the wear members become badly worn, they can be readily replaced, thereby prolonging the period of usefulness of the entire crate.

I claim:

1. The combination in a box-like structure of side and end walls each recessed at its lower corners to form angular cut-outs in the lower corners of the structure, channel-shaped runner elements embracing the lower edges of the walls, 15 angled corner brace elements overlying the meeting portions of the inner and outer surfaces of the walls and terminating above the lower edges of the walls, an angled wear element positioned in each cut-out of the lower corner of the structure, said wear member being solid and of substantially the same height as said runner elements, and means to secure said elements together and extending horizontally through the elements at points above the lower edges of the 20 25 elements.

2. The combination in a box-like structure of side and end walls each recessed at its lower corners to form angular cut-outs in the lower corners of the structure, channel-shaped runner elements embracing the lower edges of the walls, angled corner brace elements overlying the meeting portions of the inner and outer surfaces of the walls and terminating above the lower edges of the walls, an angled wear element positioned in each cut-out of the lower corner of the structure, 30 35 said wear member being solid and of substantially the same height as said runner elements, and means to secure said elements together and extending horizontally through the elements at points above the lower edges of the elements, said wear element including lateral flanges underlying the ends of the runner elements and corner brace elements.
